UNITED STATES PATENT OFFICE.

CHARLES W. SPENGLER, OF JEFFERSONVILLE, OHIO.

WHEEL-WRENCH.

SPECIFICATION forming part of Letters Patent No. 603,156, dated April 26, 1898.

Application filed December 16, 1897. Serial No. 662,200. (No model.)

To all whom it may concern:

Be it known that I, CHARLES W. SPENGLER, a citizen of the United States, residing at Jeffersonville, in the county of Fayette and State 5 of Ohio, have invented a new and useful Wrench-Operating Mechanism, of which the following is a specification.

This invention relates to wrench-operating mechanism particularly adapted for use in 10 turning nuts on bolts such as are used to secure a tire to the rim of a vehicle-wheel; and the object of the invention is to provide a simple and efficient device of this character in which the operating-shaft and the wrench- 15 carrying shaft will be connected to have simultaneous rotary movement and also simultaneous but reverse longitudinal movement to permit the wrench to follow up the nut when screwing it on the bolt or to retreat in 20 advance of it when screwing it off.

The invention also contemplates providing a device to eject the nuts from the wrench.

With these and other objects in view the invention consists of the several details of 25 construction, combination, and arrangement of parts, as will be hereinafter fully described, and particularly pointed out in the claims.

In the drawings, Figure 1 is a side elevation of my improved wrench-operating mechanism, the casing being in section, showing one 30 form of the connecting devices between the operating-shaft and the wrench-carrying shaft. Fig. 2 is an end view. Fig. 3 is a similar view looking at the other end of the device, the casing being broken away to show the gearing. Fig. 4 is a view similar to Fig. 1, showing another form of connecting device between the operating-shaft and the wrench-carrying shaft, the connecting device being 35 partly broken away. Fig. 5 is a perspective view of the connecting device for the shafts. Fig. 6 is a longitudinal section through the wrench-head, showing the manner of mounting the nut-ejector. Fig. 7 is a perspective view of the ejector detached.

Similar reference-numerals indicate similar parts in the several figures.

Referring to Figs. 1, 2, and 3, 1 indicates a hollow casing formed in two sections separable on a vertical line, detachably connected together by bolts 2. The casing is provided with alining openings 3 in its opposite sides

to receive and form bearings for the respective hubs 4 and 5 of the gears 6 and 7. The gear 6 will preferably be of less diameter than 55 the gear 7 in order that it may rotate faster. Each hub will preferably have shoulders 8 to engage the inner faces of the casing and prevent longitudinal movement of the hubs in 60 their bearings. The gears 6 and 7 are fast on the hubs and rotate with them.

The hubs 4 and 5 are each provided with a longitudinal angular bore 9 to receive, respectively, the wrench-shaft 10 and the operating-shaft 11, and these shafts are supported 65 in the hubs to slide freely therein, but to have no rotary movement in the hubs.

12 indicates the wrench-head, secured on one end of the shaft 10 and provided with an angular opening 13 to receive the nut to be 70 turned. If preferred, the wrench-head may be detachably connected to the shaft 10 in order that the head may be changed, if necessary, to adapt the device for use with nuts of different sizes. The other end of the shaft 75 10 is rounded and provided with an annular groove 14, and this rounded end fits loosely in a socket 15 and is held therein by a set-screw 16, which extends into the annular groove and permits free rotary movement of 80 the shaft in the socket, but prevents it from being withdrawn therefrom. The corresponding end of the shaft 11 is also rounded and provided with an annular groove 17, and the rounded end fits loosely in a socket 18, similar 85 to the socket 15, and is held therein by a set-screw 19 in a manner similar to that described with reference to the shaft 10. Each socket is provided with a pair of spaced ears 20 for a purpose which will be referred to hereinafter. 90

21 indicates an arm, preferably integral with the casing, although it may be secured thereto in any other manner, if preferred, and this arm extends horizontally from the casing. 22 indicates a lever or yoke pivotally connected 95 intermediate its ends to the said arm by means of a bolt 23, and each end of the yoke is provided with an elongated opening, (indicated by 24,) in each of which openings a block 25 is supported to slide freely therein. The 100 spaced ears 20 of the respective sockets straddle the respective ends of the yoke and also the blocks 25 and are pivotally connected to the latter by cotter-pins 26 or similar devices.

When the yoke is rocked on its pivot, the blocks will slide in the openings 24, and as the sockets are pivotally connected to the blocks the parts will adjust themselves when 5 the yoke is rocked in either direction by the longitudinal movement of the shafts. The opposite end 27 of the shaft 11 is shaped to receive an ordinary bit-brace, by means of which the shaft may be turned, or it may be 10 turned by any other suitable device. The casing is provided with a flange 28 at its lower end, through which bolts or screws 29 are adapted to pass to secure the casing to any suitable support.

15 Referring now to Figs. 5 and 6, it will be observed that the parts of the machine are similar to those already described, except as to the form of the ends of the shafts 10 and 11 and the yoke connecting them. In this 20 form each shaft is provided with a ball 30 on its end and a narrow neck portion 31 between the ball and body of the shaft. The yoke is in the form of an open-ended tube, (indicated by 32,) the interior diameter of which 25 is substantially equal to the diameter of the balls 30, which are intended to fit loosely therein. The tube is provided with a slot 33 at one side, extending from end to end and with an outwardly-projecting flange 34 at 30 each side of the slot. Midway their length the flanges are widened to form the ears 35, which are perforated, as indicated at 36. The end of the arm 21 projects into the tube between the ears 35, and the pivot-bolt 23 extends 35 through said ears and the arm 21. The balls 30 are inserted into the tube at its respective ends, and the necks 31 on the shafts will extend through the slot 33 and between the flanges 34, and it is evident that the yoke 40 will be free to adjust itself on the balls 30 when it is rocked on the pin 23 by the horizontal movement of the shaft and that the balls can turn axially in the yoke. The balls 30 form pivotal connections between the lever 45 or yoke and the shafts 10 and 11, and the pivotal connection is adapted to move freely longitudinally of the lever or yoke.

Referring now to Figs. 5 and 6, it will be seen that the nut-ejector comprises a rectangular block 37, from opposite sides of which 50 a pair of arms 38 extend rearwardly, the outer ends of these arms being bent to form lateral projections 39. The block 37 is adapted to work loosely in the opening 13, and the arms 38 in grooves 40, in the wrench-head, and the several parts will be so proportioned that when the lateral projections 39 engage the rear end of the wrench-head the front end of the block 37 will be flush with the front end 55 of the head, as shown in Fig. 5.

In operation the wheel will be supported in a horizontal plane in such manner as to enable the wrench 12 to fit over the nuts of the tire-bolts successively, and by turning the 60 shaft 11 rotary movement will be imparted through the gears 7 and 6 to the shaft 10 and the wrench-head 12, and it is obvious that

this rotary movement may be in either direction to turn the nut on the bolt or turn it off, as desired. When turning the nut on the bolt, the shaft 11 will be pushed forward toward the pivoted yoke, and the yoke will thus be rocked on its pivot and move the shaft 10 in the opposite direction, thereby causing the wrench-head to follow up the nut as it is 70 turned onto the bolt. In turning the nut off the bolt the nut will cause the shaft 10 to gradually retreat in front of it, and this movement of the shaft will rock the pivoted yoke and move the shaft 11 in the opposite direction. When the nut has been removed from the bolt, the ejector will have been forced rearwardly, and by pulling on the shaft 11 the lateral projections 39 will be caused to 75 engage the hub 4, and the ejector will move 80 toward the open end of the wrench-head and eject the nut.

It will be understood that changes in the form, proportion, and the minor details of construction may be resorted to without departing from the spirit or sacrificing any of the advantages of this invention.

Having thus described the invention, what I claim is—

1. In a wrench-operating mechanism, the combination with an operating-shaft, and a wrench-carrying shaft both supported to have rotary and longitudinal movement, of gearing to transmit rotary movement from one shaft to the other, and a lever fulcrumed between its ends and pivotally connected with the shafts, whereby the shafts are simultaneously reciprocated in opposite directions, substantially as described.

2. In a wrench-operating mechanism, the combination with an operating-shaft, and a wrench-carrying shaft both supported to have rotary and longitudinal movement, of gearing to transmit rotary movement from one shaft to the other, and a yoke or lever fulcrumed between its ends and pivotally connected with the rear ends of the shafts, the pivotal connections being capable of movement longitudinally of the yoke or lever, substantially as described.

3. In a wrench-operating mechanism, the combination with a supporting-casing, of an operating-shaft and a wrench-carrying shaft both supported to have rotary and longitudinal movement in said casing, and each having a ball on one end, gearing to transmit rotary movement from one shaft to the other, an arm projecting horizontally from the casing, and a slotted tubular yoke pivoted intermediate its ends on said arm and in which the said balls are loosely fitted, substantially as described.

4. In a wrench-operating mechanism, the combination with an operating-shaft and a wrench-carrying shaft, both supported to have rotary and longitudinal movement, and each having a ball on one end and a neck portion connecting the ball to the body of the shaft, gearing to transmit rotary movement from

one shaft to the other, a yoke comprising an open-ended tube having a slot extending from end to end, said yoke being pivoted intermediate its ends on a suitable support and the 5 balls on the shafts being loosely seated in the tube on opposite sides of its pivot and the neck portions of said shafts extending through the slot, substantially as described.

5. In a wrench-operating mechanism, the 10 combination with the wrench-head supported to have rotary and longitudinal movement, of a nut-ejector supported in the head to have longitudinal movement therein, substantially as described.

15 6. In a wrench-operating mechanism, the combination with the wrench-head supported

to have rotary and longitudinal movement, of a nut-ejector comprising an angular block and a pair of arms extending rearwardly therefrom, said block being loosely supported 20 in the nut-receiving opening in the head and the arms in ways in said head, and said arms projecting beyond the rear end of the head and adapted to be engaged with a fixed part, substantially as described.

25 In testimony that I claim the foregoing as my own I have hereto affixed my signature in the presence of two witnesses.

CHARLES W. SPENGLER.
